UNITED STATES PATENT OFFICE.

WILLIAM T. WELLS, OF HACKENSACK, NEW JERSEY.

LOCOMOTIVE.

SPECIFICATION forming part of Letters Patent No. 275,739, dated April 10, 1883.

Application filed May 24, 1882. (No model.)

To all whom it may concern:

Be it known that I, WILLIAM TWINING WELLS, of Hackensack, county of Bergen, and State of New Jersey, have invented certain Improvements in Locomotives and Similar Mechanism, of which the following is a specification.

This invention relates more particularly to the driving mechanism of locomotives, but may also be employed in the construction of similar mechanism for other purposes.

The invention comprises an improvement in that class of driving apparatus in which the cylinder and its piston and piston-rod are arranged vertically above the driving-wheel, the piston-rod being connected by a suitable pitman or connecting-rod with the driving-wheel, while the piston-rod is itself substantially axially coincident with a line drawn through the axis of the axle to the point of contact of the wheel with the rail or road way. This construction insures the transmission of power from the piston-rod to the wheel in such manner that the direction in which the power is exerted is always in the same direction as that in which the locomotive or vehicle propelled is going, except at certain points where the direction is perpendicular to the track, thereby preventing retardation of the forward movement of the wheel by avoiding any backward thrust, as occurs with the use of the horizontal piston-rod. As hitherto proposed, however, this apparatus has been incapable of successful practical application to locomotives, for the reason that a cylinder being rigidly connected with the boiler is liable to change its position with relation to the wheel with every jar or change in the substantially vertical position produced in the boiler by the action of the springs underneath.

My invention is designed to obviate this by enabling the boiler to move vertically without interference with the stability of the cylinder, and this I secure by interposing an elastic or otherwise flexible steam-connection between the boiler and the valve-chest of the cylinder.

Figure 1 is a front view, showing the arrangement of the parts included in an apparatus constructed according to my said invention. Fig. 2 is a detail sectional view on a larger scale, representing certain parts there-

of; and Fig. 3 is a similar view, representing a modification of my said invention.

A is an axle, upon each end of which is a driving-wheel, B, the latter provided with a 55 crank-pin, C.

The rail or road way is represented at D, the point of contact of the circumference of the driving-wheel with the said rail or road way being indicated at a. 60

E is the steam-cylinder, placed vertically above the wheel B, with its piston-rod F axially coincident with a vertical line or plane drawn from the axis of the axle A to the point a, at which the circumference of the wheel 65 rests upon the track or roadway D. This piston is connected with the crank-pin C by a connecting-rod or pitman, G.

The cylinder is attached to the frame-work of the locomotive in any suitable manner, provision being made to retain the said cylinder at a permanent or uniform distance from the driving-wheels. This is to be done by attaching it to that part of the frame-work which is independent of the movement of the boiler upon 70 its springs as said boiler rises and falls as the springs are more or less compressed by the jarring incident with the usual motion of the locomotive. 75

The boiler is shown at H, and is connected 80 with the valve-chest, or with the valve-chest of each cylinder when more than one is used, as represented in Fig. 1, by a substantially flexible tubular connection, I. This connection may be effected by a metal pipe placed in such 85 manner that its flexure will enable it to respond to the movement of the boiler with reference to the cylinder; or, instead of this, the connection may be formed of a suitable flexible pipe—such, for example, as properly prepared rubber or other tubing—as indicated in 90 Fig. 3. Inasmuch as the connection I is enabled to yield to the variation in distance between the boiler and cylinder as the boiler moves up and down, it follows that no wrenching or other injurious effect is exerted upon 95 the cylinder in the operation of the apparatus, and by this means I enable the principle of propulsion hereinbefore specified to be practically applied with advantageous results, 100 whereas without my said invention the apparatus would quickly destroy itself, and to all

practical intents and purposes will be of little or no use.

I do not claim any combination of parts shown in British Letters Patent No. 373 of 5 1856, as the mechanism described in said patent is different from that embraced in my said invention, and incapable of producing the results effected by my said invention; but

What I claim as my invention is—

10 In an apparatus for the propulsion of locomotives and the like, the combination of the following elements, to wit: a cylinder and its piston and piston-rod, placed vertically above the driving-wheel, the piston-rod being 15 connected by a suitable pitman or connecting-rod with the crank-pin of the driving-wheel, and substantially coincident with a line drawn

through the axis of the axle to the point of contact with the wheel of the rail or road way, the frame-work carrying the cylinder independent of the movement of the boiler, the boiler supported upon springs in the usual or any suitable manner, and the flexible or yielding tubular connection between the steam-space of the boiler and the valve-chest of the 20 cylinder, the whole constructed, combined, and arranged for joint use and operation substantially as and for the purpose herein set forth.

WILLIAM TWINING WELLS.
